UNITED STATES PATENT OFFICE.

JOHN A. DORMER AND JAMES GUNNELL MALONE, OF DETROIT, MICHIGAN.

CRUSHING MACHINE.

Application filed September 29, 1926. Serial No. 138,375.

This invention relates to new and useful improvements in rock or ore crushing machines and has especial reference to that type of crusher wherein the material to be crushed is deposited between a pair of spaced conical plates arranged to rotate together, one of the said plates being capable of a tilting movement with respect to the other plate.

An object of the present invention is to provide a simplified and improved mechanism in combination with such crushing plates, whereby such machines are made more flexible.

Another object of the invention is to increase the durability of such machines and insure a low economical maintenance.

A still further object of the present invention is to eliminate the undesirable friction accompanying the use of eccentrics to tilt the tilting plate shaft, by the use of rollers engaging a cam carried on the end of the tilting plate shaft.

A still further object of the invention is to provide a crushing machine effecting a greater crushing power, which utilizes a single drive, and saves in parts and reduces power input.

Other objects of the invention will appear hereinafter.

30 In the accompanying drawing:

Figure 1 is a vertical longitudinal sectional view of the crushing machine;

Fig. 2 is a cross sectional view upon the line II-II of Fig. 1, of the mechanism for transmitting a tilting movement to one of the crushing plates;

Fig. 3 is a detail sectional view taken on the line III-III of Figure 1, showing the driving key by which both plates are caused 40 to rotate together;

Fig. 4 is a detail longitudinal sectional view of the gyratory mechanism effecting tilting of the crushing plates and showing a slightly modified construction;

45 Fig. 5 is a vertical sectional view taken on the line V-V of Figure 4; and

Fig. 6 is a sectional detail view showing a flexible connection between crusher head and end of the outer casing.

50 Like numerals of reference indicate corresponding parts.

Referring now to the drawings:—

Reference character 10 indicates the machine frame or support having formed in 55 its forward end a bearing 11 and in its rear

end another bearing 12 aligning with the said bearing 11, said rear bearing having a rearward circular extension 13 preferably shaped as shown and provided with a counterbore 14.

Journalized within the bearings is a hollow shaft 15 having at its forward end a cup-shaped extension or socket 15^a projecting beyond the bearing 11. Said hollow shaft 15 contains therein a tapered shaft 16, the forward end of which is adapted to carry a spherical member, or crusher head 17 provided with a suitable bearing surface upon which the conical crushing plate 18 is secured by any suitable means desired, such as a circular plate 19 engaging an axial opening in the plate 18 and secured to the end of the shaft 16 by a screw 8.

The cup-shaped extension 15^a of the shaft 15, preferably has formed thereon one or more lugs 20 properly positioned for engagement within slots 21 formed in the outer periphery of the spherical member or crusher head 17, whereby shaft 15 is caused to drive the shaft 16. The surface of the head 17 opposing the plate 18 is preferably faced with a smooth lining 7.

An outer or end cover plate 22 having secured thereto an outer conical crushing plate 23 in opposed relation to the plate 18, is bolted to and spaced from the flanged cup-shaped extension 15^a of the shaft 15, by the bolts 24 and spacers 25, and a series of shims 26 is preferably placed on these bolts adjacent the spacers to give the desired adjustment of cover plate 22 relative to the head 15^a and of the space between the opposed conical crushing plates 18 and 23. Said cover plate 22 and conical plate 23 are formed with registering central apertures 27 into which a chute 28 projects for feeding rocks or ore into the hollow interior of or space between the crushing plates. A housing (not shown) may be provided for enclosing the crushing end of the machine.

To the rear end of the solid shaft 16, is keyed a cam 29 which rests upon a plurality of tapered rollers 29^a carried within a cage 30, the said rollers being arranged to roll within a race or ring 31 which is set within said counterbore 14, and retained in place by an annular offset member 32, which also bears against the side of the cage 30, retaining it in proper position as well.

The cam 29 is provided with an annular

extension 33 on its outer end, having a series of threaded apertures to receive bolts 34 for securing an annular plate 35 to the end of the cam over the end of the shaft 16. Said plate engages an annular groove formed in a nut 36 on a screwthreaded stud 37 which is made integral with or rigidly secured to the end of the shaft and projects axially therefrom. By this means, a longitudinal adjustment of the cam 29 on the shaft 16 is effected.

A gear wheel 40 is preferably keyed on the hollow shaft 15 between the bearings 11 and 12 for driving the crusher, and these bearings are protected from dust and foreign matter by annular cooperating tongues and grooves 41 and 42 formed in the bearings and shaft 15, and annular ring plates 43 are mounted on the shaft adjacent the ends of the bearings to prevent dust from entering the grooves.

In Figure 4 there is shown a modification of the means for oscillating the shaft 16. This mechanism comprises the mounting of the cam 29 loosely upon the end of the shaft 16 instead of having the same keyed thereto, the cam being supported by tapered rollers 29^a, as in Figure 1, to roll thereon.

There is provided a ring 44 suitably kept from revolving by means of a lug 48 projecting from the end cover plate and engaging within a bifurcated lug 49 formed integral with said ring 44. Said ring 44 is formed with a lateral flange 45 having internal teeth formed within its periphery.

An annular gear 46 is suitably fixed to the end of the shaft 16 adjacent said cam 20, and a series of small gears 47 are carried upon the outer side of the cam, meshing with the teeth of the gear 46 and the flanged ring 44.

In Figure 6 a fragmentary section of the crusher head 17 and the socket formed on the shaft 15 is shown provided with a flexible annular member 35. This member 35 slides under ring 36, and the opposite circumference of the flexible member is suitably supported upon a substantially flat ring 37 jammed within a crevice 38 between the surface of the crusher head 17 and the plate 18. Sufficient slack is left in the flexible member to accommodate maximum relative movement between the shaft 15 and the crusher head 17.

In order to prevent damage or strain from being placed upon the various parts of the machine when the machine is run with the crusher plates empty or nearly so, there is provided a thrust collar 50 suitably secured upon the shaft 16, which abuts against the said cam 29 and the end of the hollow shaft.

In operation, power applied to the gear 40 rotates the hollow shaft 15 and the outer crushing plate which is carried thereby.

The lugs 20 formed on the socket shaped

extension of the shaft 15 engage within the slots 21 of the spherical member 17, causing the shaft 16 to rotate in unison with it. The rear end of the shaft 16 resting upon the cam 29, which, in actuality, comprises the inner member of the tapered roller race, has imparted to it an oscillatory or gyratory motion.

The cam 29 rolling over the rollers advance at a greater velocity than the rollers and in so doing the higher and lower spots on the periphery of the cam 29 must pass the rollers and so develop a gyratory motion in the end of the shaft 16 to which the cam is secured. A sufficient clearance being present to accommodate for the tilting of the shaft 16 the spherical member or crushing head moves within the cup-shaped socket formed in the end of hollow shaft 15, tilting the conical crusher plate carried thereby and effecting the crushing operation upon the outer conical plate.

Materials to be crushed are fed through the chute and lodge between the plates, the centrifugal force due to both plates rotating in unison as hereinbefore explained, directs the material outward to the peripheral restricted space between the plates where the crushing action takes place, and as the materials are crushed by the progressive advancing of the plates toward one another, the crushed material is discharged through the space between the peripheries of the plates, and the process repeated.

It will be obvious that the ring cam 29 hereinbefore described develops a multiplicity of eccentric throws per single revolution of the crusher plates, and it will be understood that by varying the number of rollers the number of relative tiltings of the plates may be increased or diminished, as may be desired. The gyratory mechanism may easily be adjusted for wear by the nut on the end of the shaft 16. Wear in the plates may be adjusted by removing one or more shims on the bolts 24 and thereby spacing the outer plate nearer the inner plate.

In the operation of the Figure 4 and Figure 5 type of construction, the gear 46 being fixed to the shaft 16, drives the gears 47 around the stationary ring 45, the gears in turn actuating the cam 29, causing the same to revolve upon the rollers 29^a at a speed different than that of the shaft 16. This form of the invention, it will be understood, provides for a variable rate of regulation of the crushing strokes of the machine.

From the foregoing, it will be seen that there is provided a machine of simplified construction, using only a single drive gear, possessing few parts, materially eliminating friction, and providing for a wide range of crushing blows per revolution of the crushing plates.

Modification of the above may be made within the spirit and scope of the invention.

What we claim is:—

1. In a crushing machine, the combination with a driven hollow shaft having a socket extension, a conical crushing plate carried thereby, a shaft within said hollow shaft having a crushing head and a conical crushing plate oppositely disposed to first named plate, means to connect said plate with said socket whereby both shafts are driven in unison, a cam secured to the opposite end of said shaft, rollers engaging with said cam and arranged between said cam and a stationary bearing surface, and means to adjust the cam longitudinally.
2. A crushing machine including oppositely disposed crusher plates carried on inner and outer shafts, means to drive both shafts in unison while permitting a relative tilting of the plates, and out of round means in the bearing of one of the shafts and fixed on said shaft to rotate therewith whereby a gyratory movement is transmitted to that shaft to provide a tilting of the crusher plate carried thereby.

3. A crushing machine including oppositely disposed spaced crusher plates, shafts supporting the plates, the inner shaft bearing in the outer shaft in a ball and socket joint at a point adjacent said plates, mechanical means to lock the two shafts together without interference with the freedom of the ball and socket connection, means to drive the outer shaft, a bearing for the end of the inner shaft, and means within said bearing to produce a gyratory movement in the said shaft whereby the plate carried thereby is progressively advanced and withdrawn from the opposed plate during the rotation of both plates in unison.

4. In a crushing machine, the combination with oppositely disposed crushing plates adapted to rotate in unison and have a relative tilting movement with respect to each other, of a hollow shaft carrying one plate, a second shaft within said shaft carrying the other plate, and a mechanism to produce said tilting movement of the last mentioned plate

including a ring cage provided with rollers in the end of the machine opposite said plates, a cam keyed to said tapered shaft arranged to travel on the rollers for transmitting a gyratory movement to the shaft.

5. A crushing machine comprising in combination, shafts, bearings for the outer shaft, a ball and socket bearing in the end of the outer shaft to receive one end of the inner shaft, a roller bearing for the opposite end of the inner shaft, a cam keyed onto said opposite end of said inner shaft and travelling on said rollers to produce gyratory movement in the inner shaft, means to lock the inner and outer shafts together without interfering with the freedom of relative movement between the shafts, and oppositely disposed crushing plates carried by the said shafts and actuated toward and away from each other in a tilting manner by said cam to crush objects contained between said plates.

6. A crushing machine comprising, in combination, two shafts, a ball and socket bearing in the end of one shaft to allow said shaft to be tilted relative to other shaft, opposed plates attached to each shaft in such a manner that one shaft and plate are relatively tiltable, an inner ring and an outer ring, rollers traveling on said rings, a roller cage for containing and spacing said rollers, and auxiliary driving mechanism to rotate said inner ring at a greater or lesser velocity than said shaft.

7. A crushing machine including oppositely disposed crushing plates, shafts supporting said plates, means to drive both shafts in unison while permitting a relative tilting of said plates, means to cause one shaft to move eccentrically in respect to the other, effecting a relative tilting movement between the plates, a cam bearing for one of said shafts, and a gear system to drive said cam bearing for providing a speed ratio between last named shaft and said cam ring.

In testimony whereof we affix our signatures.
